UNITED STATES PATENT OFFICE.

HIPPOLYTE MARCEL LAMY-TORRILHON, OF PARIS, FRANCE.

REFINING.

Application filed April 10, 1924, Serial No. 705,717, and in France April 14, 1923.

The invention relates to apparatus for the continuous or discontinuous treatment of all sorts of materials which are to be refined or from which it is desired to remove some 5 constituents.

The process consists essentially in causing the material under treatment to be traversed by a current of vapour or gas and in recovering, when the treatment is finished, the heat 10 contained in the vapours or gases which have achieved their purpose.

The apparatus is characterized essentially by the combination of a row of evaporators or vaporizers which are arranged according 15 to the multiple action principle, that is to say in which the vapour of the first action is used for evaporating the liquid contained in the second action, and so on for actions and of a column adapted to treat the materials in a continuous manner and which 20 column is divided into a certain number of elements every one of which receives the vapour passing from one of the elements to the following one, so that the economy of 25 vapour consumed by the column is comparable to that which is obtained with a multiple action apparatus for the purpose of evaporating a certain weight of water.

In order to be better understood, the annexed drawing, given by way of example 30 only, shows a construction of apparatus based upon this principle and used for example for deodorizing oils through the action of a current of steam.

The column in which the oil is treated is composed, for example, of three sections or 35 elements 1—2—3. Every one of these sections comprises a certain number of perforated plates 4, 5, 6, 7, 8, 9, allowing the 40 steam to bubble through the oil.

The oil passes downwardly through all the sections of the column. In passing from the one to the other the oil passes heaters 45 10, 11 which allow of heating up this oil to the required temperature.

The steam is led into every one of the sections through ports 13, 14 and 15, respectively connected with the elements of a three action evaporator in which, for example, the 50 steam which is generated at 16, after having passed upwardly through the section 1 of the column comes out at 19 in order to enter into the set of tubes 17^a so as to produce, at 17, a fresh quantity of steam which enters 55 at 14 into the second element of the column; the steam comes out at 20, so as to enter into

the set of tubes 18^a of the third evaporator; then the steam formed at 18 is introduced at 15 into the third element of the column. The steam leaving at 21 this third element is 60 condensed in any suitable apparatus, for instance, in a barometric condenser 22 in which a certain amount of vacuum is maintained by means of any convenient device, such as a vacuum pump, and the like. In the 65 drawing, this vacuum apparatus 23 is supposed to be a steam trompe or blower, the steam coming from this trompe and conveyed through a pipe 23^a is used for heating the set of tubes 16^a of the first evaporator 70 16. The condensation waters coming from the tubes of the evaporators 16, 17, 18 pass through heat exchangers 26, 27, 28 in which a pump 33 forces the feed water supply for the multiple action evaporator. 75

The water or other fluid the vapours of which are to act upon the material under treatment enters at 29, for example, into the first evaporator and passes, through a pipe 30, from the first evaporator to the second 80 one, then through a pipe 31, from the second to the third one, and so on.

The material which has been treated leaves the column at 43 and passes through a heat exchanger 24 in which it gives up its heat 85 to the material which is to be treated which arrives at 25^a and enters into the column at 25.

According to the new method of treatment, it is possible to obtain an important 90 economy. In fact, in all of the processes consisting in submitting the oils to a current of steam in order to deodorize them, whether the operation is carried out in a vacuum or at atmospheric pressure, in a discontinuous manner in digester, or in a continuous manner, causing the oil to flow into columns of the same kind as those which are used in a distillery, the steam, after having 95 done its work on the oil, is directly exhausted into the atmosphere or condensed. In the present process the sensible heat and the latent heat of vaporization of the steam are recovered. 100

The forms of construction of the apparatus can of course be modified in many ways, without departing from the principle of the invention. 105

In the preceding case it has been supposed that the apparatus was working with steam, but of course the principle of the invention can be carried out, whatever the nature of 110

the vapour as used may be, as also the nature of the liquid with which the evaporator is supplied; this principle can be applied not only in connection with the refining of oils but whenever it is desired to separate two or more volatile bodies, even in case the operation would take place at temperatures which are lower than the boiling point of the most volatile liquid. The apparatus can 10 also be used for the treatment of powdered solid substances; for the column is then substituted an apparatus which allows the material to pass from one plate to the other, of the same kind, for example, as certain 15 dryers, kilns, and the like.

It must be understood that the operation of the new system is independent of the pressure of the evaporators relative to the atmosphere; in other words, it is only necessary 20 that the difference in pressure between one evaporator and the other be sufficient so as to secure, under good conditions, the vaporization of the liquid and the circulation of the vapours in the column, whatever the 25 value of these pressures may be relative to the atmospheric pressure. Vacuum is therefore in no way unavoidable for the obtention of the desired economical effect. It will be sufficient to operate in the first evaporator 30 with vapour at a pressure which is sufficient for obtaining the necessary drop at every stage.

The stages can also be in any number which is only limited by the working conditions and the cost price. The exhaust of the 35 condensation waters from the heaters such as

26, 27, 28 can take place through any suitable means, through a pump for example, a barometric column, vacuum flasks, and the like, in case these exhausts are to take place 40 at a lower atmospheric pressure.

Claims:-

1. In an apparatus for the continuous treatment of materials, a distillation column sub-divided into a number of elements, means for progressively heating these elements, a multiple effect apparatus having a series of multiple effects equal in number to number of elements of the said column, connections permitting the vapor produced 50 in each multiple effect element to traverse an element of the column and then to pass into the following multiple effect element.

2. In an apparatus for the continuous treatment of materials, a distillation column sub-divided into a number of elements, means for progressively heating these elements, a multiple effect apparatus having a series of effects equal in number to the number of elements of the column, connections permitting the vapor produced in each multiple effect element to traverse an element of the column and then to pass into the following multiple effect element, heat exchangers at the exit of the multiple effect 60 apparatus and at the exit of the column to heat the liquids entering said column and said multiple effects.

The foregoing specification signed by me this 29th day of March 1924.

HIPPOLYTE MARCEL LAMY-TORRILHON.
